CLAIM

The ornamental design for a rolled sheet retainer, as shown and described.

DESCRIPTION

FIG. 1 is an isometric view of a first embodiment of a rolled sheet retainer of the present invention;
FIG. 2 is a view of FIG. 1, as taken from the right side;
FIG. 3 is an end view elevation of FIG. 1;
FIG. 4 is a top plan view of FIG. 1;
FIG. 5 is a bottom plan view of FIG. 1;
FIG. 6 is an isometric view of a second embodiment of a rolled sheet retainer of the present invention;
FIG. 7 is a view of FIG. 6, as taken from the right side;
FIG. 8 is an end view elevation of FIG. 6;
FIG. 9 is a top plan view of FIG. 6;
FIG. 10 is a bottom plan view of FIG. 6;
FIG. 11 is an isometric view of a third embodiment of a rolled sheet retainer of the present invention;
FIG. 12 is a view of FIG. 11, as taken from the right side;
FIG. 13 is an end view elevation of FIG. 11;
FIG. 14 is a top plan view of FIG. 11; and,
FIG. 15 is a bottom plan view of FIG. 11.
